TRAFFIC CONTROL APPARATUS

John L. Barker, Norwalk, Conn., assignor to Automatic Signal Corporation, East Norwalk, Conn., a corporation of Delaware

Application November 20, 1939, Serial No. 305,233

26 Claims. (Cl. 177—337)

This invention relates to traffic control apparatus for control of the right of way of traffic at the intersection of two or more streets or traffic lanes. More particularly it relates to an improved traffic control system or apparatus of the traffic actuated type, employing traffic detecting devices or detectors in the intersecting lanes, traffic right of way signals at the intersection and a time controlled operating mechanism operated by the detectors to display the right of way signals to the several lanes successively for time periods responsive to traffic actuation of the respective detectors.

Some prior traffic actuated signal systems have employed a resettable timing device for timing a part of the right of way signal period for a street under control of the traffic actuated detector of that street so that actuations of the detector by vehicles approaching the intersection during the right of way period reset the timing device successively and cause it to repeat its time period, and thus prolong the right of way signal display for such vehicles. The time period for such a timing device is usually of only a few seconds duration so as to be not much greater than the average time spacing between successive vehicles approaching in moderately heavy traffic, and thus if one or more vehicles are waiting on one street against a stop signal for example the go signal period on the other intersecting street will be terminated and right of way transferred to the first street in event that the time gap between approaching vehicles on such other street exceeds a reasonable value indicating that approaching traffic using the go signal is so widely separated that it would be more efficient to transfer right of way to the waiting traffic on the opposite street.

In the traffic control system disclosed in the copending application, Serial Number 74,422, now United States Patent Reissue 21,377, of Harry A. Wilcox, which has a common assignee with the present application, an improvement in systems of the type described above is provided by progressively reducing the time period of the resettable timing device for the right of way period on one street responsive to arrival of successive vehicles which increase the traffic waiting on the other street.

The present invention provides a further improvement in systems of this general character in that the timing period of the resettable timing device determining the gap interval at which right of way may be terminated is progressively

reduced during the right of way period of one street by either one or both of two factors: (1) by the arrival of a series of quite closely spaced vehicles or (2) by the passing of time following the arrival of the first waiting vehicle on the other street which does not have right of way.

The effect of reducing the time period of the gap interval timer is to require moving traffic to maintain close spacing to retain right of way.

It will be appreciated by those skilled in the art of traffic signalling that traffic flow has considerable variation from moment to moment as well as hourly, daily and seasonal variations.

Such variations may result for example in having only one or two vehicles waiting on a street at the beginning of the go signal period on a street and then after several seconds having a fairly closely spaced group of vehicles arrive. It is therefore unsafe to employ a short time setting initially for the resettable timer which establishes the gap interval which will release right of way, and the time ordinarily is started with a time period providing a considerable margin above the gap interval of closely spaced moving vehicles to avoid cutting off the right of way signal too early in the face of approaching traffic. As the right of way period continues however and the timer is reset by moving vehicles, any vehicles waiting for right of way on the other street should not be held too long and it is desirable to reduce the time period of the resettable timer to take advantage of any appreciable time gap appearing in the moving traffic which indicates that the volume of flow of the moving traffic is decreasing.

The present invention provides apparatus for reducing the allowable gap interval in accordance with the factors (1) and (2) outlined above, both of which factors provide improved operation without the feature of progressive reduction of the gap interval in accordance with the number of waiting vehicles disclosed in the copending application, Serial Number 74,422, referred to above, but offer particularly marked efficiency and sensitivity to slight changes in flow of heavy traffic in combination with this feature of the said copending application. The invention is described and illustrated in its preferred embodiment in connection with the apparatus of the copending application and is also individually described.

In systems of this general character it is the usual practice to provide a maximum limit timer for terminating right of way on one street after

a certain maximum period of substantial continuous moving traffic on the one street if traffic is waiting on the other street, and the present apparatus includes this feature but it is one aspect of the invention that the reduction of the gap interval timing period may be made so pronounced as to go below the minimum possible spacing of moving traffic and thus force release of right of way after a maximum time period in lieu of the use of a separate maximum limit timer.

Also in systems of this general character in which vehicles approaching the intersection on a go signal extend the period of display of said signal, the go period is preferably divided into at least two parts the first part being identified ordinarily as an "initial interval" or "starting interval" for the purpose of enabling accumulated waiting traffic to get into motion and the second part comprising a unit time extension interval which is repeatedly reset by vehicles in the stream of moving traffic. The unit interval of the second part is variously designated in the art as a vehicle protection period, right of way extension period, gap limit interval or vehicle interval. The first part will be referred to herein uniformly as the initial interval and the unit extension period of the second part will be referred to herein as the vehicle interval.

In the present system as in prior types of vehicle actuated systems the actuation of traffic detector in a traffic lane in which the stop signal is being displayed causes the right of way to be transferred to that lane at the first opportunity. If there is no traffic entering the intersection from the lane in which the go signal is being displayed a caution signal is usually immediately displayed in said lane and after a short period the right of way is transferred to the lane in which the stop signal was being displayed.

If traffic is moving in the lane wherein the "go" signal is being displayed the actuation of the traffic detector in the lane in which the "stop" signal is being displayed causes the right of way to be transferred thereto at the first break of a predetermined time in the said moving traffic. If no such break occurs in said moving traffic the right of way will be transferred at the end of a predetermined maximum period usually provided by a different timing element.

This system, like some previous traffic actuated systems is arranged so that the timing of the "initial interval," the first part of the "go" period, can, before the beginning of said "initial interval," be preadjusted between a predetermined minimum value and a predetermined maximum value, by successive actuations of the traffic detector in the lane in which the "stop" signal is being displayed so that when said lane shall next be given the "go" signal the "initial interval" of said "go" signal display period will be timed in conformance with the volume of the traffic waiting in said lane, to the end that a large number of waiting vehicles will be granted a longer initial interval than will be granted to a small number.

In this system the traffic detectors can be located at a distance from the intersection customary in the older types but it is entirely feasible, especially if the variable initial interval is employed, to locate them considerably farther from the intersection (two or three hundred feet or more for example) thereby facilitating the counting of larger numbers of waiting vehicles which will increase the effectiveness of traffic ap-

proaching a stop signal in controlling the signal timing.

With the system adjusted to give a pronounced reduction of the vehicle interval after the accumulation of a certain amount of traffic approaching a stop signal a considerable degree of coordination between adjacent intersections can be obtained solely by the pressure of traffic itself without any electrical interconnection since the effect of such a group of vehicles approaching successive intersections equipped with this system will be to so reduce the vehicle interval for cross traffic at each intersection as at any time subsequent to the cross street initial interval to practically seize the right of way at intersection after intersection thereby favoring uninterrupted progress to a sufficiently large compact group of vehicles.

Cross traffic will however be protected against unreasonable interruption since the cross street initial interval is timed in advance in accordance with the number of vehicles waiting on the cross street and is not reducible by main highway traffic, and in addition either a maximum limit to right of way on the main highway or a reduction of the main highway vehicle interval by accumulation of waiting cross street traffic, or both, serve to protect the cross street traffic.

It will be appreciated that traffic is often heavier inbound toward the central area of a city in the morning and heavier outbound in the afternoon, and that in such cases the automatic natural coordination effect above noted with this invention will be particularly pronounced on the main traffic arteries.

It is a general object of the invention to provide an improved street traffic control apparatus that is very closely responsive to changes in the volume of traffic so as to transfer right of way to waiting traffic on one traffic lane upon occurrence of a relatively small gap in moving traffic on an interfering traffic lane.

It is another object to provide an improved system in which vehicles awaiting the right of way in one lane will facilitate yielding the right of way from the other roadway by reducing the time allotted to each vehicle entering the intersection from such other roadway.

It is another object to provide an improved apparatus in which transfer of right of way from moving traffic on one lane to waiting traffic on an interfering lane is controlled a traffic actuated timing mechanism which establishes a maximum time limit for the spacing between vehicles in the moving traffic and in which such spacing time limit is adjusted responsive to variations in the actual time spacing of vehicles in the moving traffic as determined by actuations of the timing mechanism by traffic.

It is a further object of the invention to provide an improved apparatus in which transfer of right of way from moving traffic on one lane to waiting traffic on an interfering lane is determined by the time spacing of vehicles in the moving traffic lane reaching a maximum time spacing limit which is established by a timing device and which is reduced responsive to closely spaced vehicles in the moving traffic.

It is a further object of the invention to provide an improved apparatus in which transfer of right of way from moving traffic on one lane to waiting traffic on an interfering lane is determined by the time spacing of vehicles in the moving traffic lane reaching a maximum time spacing limit which is established by a timing

device and which is reduced progressively responsive to passage of time while traffic is waiting on the interfering lane.

It is another object to provide improved traffic right of way control apparatus for interfering traffic lanes having means actuated by traffic in the lanes and a timing device controlling transfer of right of way from one lane to the other lane at the end of its timing period and arranged to reset to repeat its time period responsive to operations of the traffic actuated means in said one lane having right of way, and also being arranged to have its time period reduced responsive to closely spaced such actuations and responsive also to passage of time after the first actuation by traffic waiting on the other lane not having right of way.

It is another object of the invention to provide improved traffic control apparatus having a timing mechanism controlling termination of right of way at the end of its time period and arranged to be reset to repeat its time period responsive to vehicles approaching the intersection on one lane having right of way, and in which the length of the timing period of such device is reduced by a combination of factors including the amount of traffic waiting and the length of time traffic has been waiting for right of way on the other traffic lane and close spacing of vehicles on the lane having right of way.

An embodiment of the features of the invention will now be described with reference to the drawings in which Figure 1 is a schematic plan view of an intersection showing the location of traffic detectors, signals and operating mechanism of a traffic control system employing the present invention.

Figures 2 and 3 combined represent a schematic circuit diagram of a traffic control system employing the present invention in combination with one form of the apparatus of the copending application, Serial Number 74,422, now United States Patent Reissue 21,377.

Figure 4 is a schematic circuit diagram of the part of the apparatus of Figs. 2-3 providing adjustment of the time period of a maximum vehicle spacing limit timer responsive to the actual spacing of traffic moving having the right of way, in accordance with one feature of the present invention.

Figure 5 is a schematic circuit diagram of the part of the apparatus of Figs. 2-3 providing adjustment of the time period of a maximum vehicle spacing limit time responsive to passage of time, in accordance with another feature of the present invention.

Figure 6 is a plan view of a group of adjacent intersections equipped with this system showing one example of the location of signals, traffic detectors and timer housings.

Referring now to Fig. 1 right of way signals 10 are shown at the center of the intersection of two streets NS and EW, traffic detectors 12 are located at some distance from the intersection on the NS street and traffic detectors 13 are similarly located in the EW street. These detectors are located preferably in position to be actuated only by traffic approaching the intersection but may if desired be of a directional type such as disclosed in Patent Number 2,077,924 granted to Charles D. Geer and John L. Biach on April 20, 1937, for example so as to be actuated only by traffic approaching the intersection. The control mechanism 11 is illustrated sche-

matically as connected to the detectors and signals.

Any type of visual or audible signal can be used in this system but the customary red, yellow and green traffic lights are preferable inasmuch as motorists and pedestrians are now generally familiar with the significance of these colored lights. The signals are illustrated in Fig. 1 as grouped at the center of the intersections but it will be appreciated that they may also be located at other appropriate points at the intersection either grouped or separated.

The traffic detectors may be of any desired form such as a mechanical switch in which the pressure exerted by the weight of a passing vehicle flexes a resilient plate to make a contact, or an energy beam is directed across a traffic lane so as to be interrupted by traffic approaching the intersection. A common form of the latter 20 type is a light beam directed across a traffic lane with a photo electric cell arranged as a receiver. Still another type of detector is an electromagnetic device in which the vehicle disturbs a magnetic field and thereby operates a relay in the control. Any of these or other types of traffic 25 detectors such as a push button for use of pedestrians will operate satisfactorily in this system.

Examples of suitable forms of the mechanical switch type of traffic detector are disclosed in 30 Patent Number 1,928,472 granted to H. A. Wilcox, Jr. on September 26, 1933, and Patent Number 1,950,490 granted to C. D. Geer and E. D. Stirlen on March 13, 1934, for example.

The operating mechanism 11 of Fig. 1 controls 35 the signals under cooperative control by timing devices included in the mechanism and by the traffic detectors.

A preferred embodiment of this mechanism employing the invention in combination with one 40 form of the apparatus of the aforesaid copending application, Serial Number 74,422, is shown in Figs. 2 and 3. This embodiment employs a multiple rotary line switch or stepping switch and grid controlled discharge tubes and because of 45 the sharply defined "breakdown" voltage of this type of tube great accuracy is possible in timing the various intervals. Moreover since their grid potential determines their "breakdown" voltage these tubes can be adjusted to compensate for 50 variations in tube characteristics by connecting the grid to an appropriate potentiometer tap when tubes are replaced. Thus the accuracy of the timing of the various intervals can be maintained independent of variation of tube characteristics in different replacement tubes.

The stepping switch shown in Figs. 2-3 has 55 eight positions. A stepping switch of more than eight positions can be used as an eight position switch if desired by providing rapid stepping switch 60 through the extra positions in accordance with well known methods.

It will be appreciated that a multiposition 65 rotary camshaft and cam operated switches and associated step-by-step driving mechanism could be employed in lieu of the rotary stepping switch shown for purpose of illustration.

A complete cycle of operation of the signals by the stepping switch including right of way 70 periods for the respective NS and EW streets and amber change periods for the same is outlined in the chart at the bottom of Fig. 3, showing the eight stepping switch positions and the corresponding signal indications and the names given 75 to the several intervals in the respective stepping

switch positions to more readily identify their functions.

In Figs. 2 and 3 negative A. C. power is supplied through the wire designated by a minus sign enclosed in a circle and extending vertically through substantially the middle of the figures. At the bottom of Fig. 3 this wire is identified as grounded A. C. Positive A. C. is supplied through wires designated by a plus sign in a circle at the right and left sides of these figures and positive D. C. is designated by a plus sign in a square at the right and left sides of these figures. Negative D. C. power is designated by a minus sign in a square at the middle of the top of Fig. 3 and it will be noted is maintained at a relatively more negative potential than the negative A. C. by means of the potentiometer PZ6—PZ1.

The six contact banks of the stepping switch are shown somewhat to the right of the vertical negative power wire near the middle of the figures and are identified as banks SB1 to SB6 respectively with each of the contacts numbered 1 to 8 to correspond with positions 1 to 8 of the stepping switch. The several wipers W1 to W6 inclusive are shown in position 5 between positions 4 and 6 and are arranged to be operated in unison across the contacts of their associated contact banks from one position to another by operation of the stepping switch driving magnet DM shown in the lower left part of Fig. 3.

The remainder of the apparatus represented on the part of Fig. 2 to the right of the negative power is in general effective to cooperate with the apparatus of Fig. 3 to call the right of way to the EW lane and to hold the right of way thereon. In like manner the apparatus represented by that part of Fig. 2 to the left of the power wire is effective to cooperate with the apparatus of Fig. 3 to call or hold the right of way on the NS lane.

At the top of Fig. 2 are shown the two sets of signals representing the customary green, yellow and red lights, numbers Z48 to Z50 being displayed to the EW traffic whereas numbers Z45 to Z47 are displayed to the NS traffic.

The traffic detectors located respectively in the NS and EW lanes are represented by Z51 and Z52. Relay EZ is responsive to actuations of detector Z51 and relay FZ operates in response to actuations of detector Z52.

The operation of relay FZ starts a sequential operation which calls the right of way to the EW lane and when the right of way has been given to the EW lane, operation of this relay tends to hold it there. Similarly relay EZ operates to call and hold the right of way on the NS lane.

By opening or closing switches Z68 and Z69 the apparatus can be caused to normally operate as a reverting, arterial or floating system. The closure of both switch Z68 and switch Z69 will in the absence of traffic cause the right of way to normally revert periodically from lane to lane. This system of operation is commonly called the reverting system.

If switch Z68 is closed and switch Z69 is open a NS arterial system results in which the right of way will normally remain on the NS lane until called by traffic to the EW lane. After the EW traffic has cleared the intersection the right of way will automatically revert to the NS lane. In the event of continuous EW traffic under the above system the right of way will periodically revert to the NS lane, and remain there as long as NS traffic may require it up to a predetermined limit.

If switch Z69 is closed and switch Z68 open the system will operate arterial EW under which the EW lane instead of the NS lane will be the artery. The right of way will normally remain on the EW lane until called by traffic to the NS lane, from which lane it will revert to the EW lane when the NS traffic has cleared the intersection or has held the right of way on the NS lane for a predetermined time.

If switches Z68 and Z69 are both open the apparatus will operate as a floating system under which the right of way will normally remain on the lane to which it was last called until traffic on the cross lane requires it.

Under all of these systems of operation traffic on each lane can hold the right of way up to a predetermined period against waiting traffic in the cross lane and in addition automatically put in a call for the return of the right of way to the lane from which it is being transferred if at the time of such transfer a vehicle interval has been initiated by a detector actuation in said lane within a predetermined time prior to said transfer of the right of way or if the vehicle interval prevailing thereon at the time of such transfer has by waiting cross traffic been reduced to less than a predetermined magnitude.

The various time intervals are timed by several timers including an initial interval timer, a maximum timer, a variable vehicle interval timer and a normal vehicle interval timer. The several timers are of the "static" or electronic type employing the time required to charge a condenser slowly through a control resistance from a D. C. power supply to the breakdown voltage of a gaseous discharge tube which thereupon passes current to operate a relay. The discharge tubes employed in the present embodiment are of the three electrode type in which the negative grid bias controls the breakdown voltage to initiate conduction in the anode-cathode circuit, the breakdown voltage being substantially proportional to the grid bias over a considerable range.

The initial interval timer has its time interval adjusted in accordance with accumulated waiting traffic for timing the initial intervals in positions 1 and 5 but is used as a definite interval timer also in the rest positions 2 and 6 and in the amber positions 4 and 8. For timing the initial interval its time period is adjusted substantially in accordance with the number of waiting vehicles by charging a condenser during the initial interval from an initial voltage predetermined by the number of such waiting vehicles.

When the stepping switch is in its traffic timed positions 3 or 7, three timers run concurrently. One of these, the maximum timer, is not subject to vehicle control. The other two, the variable vehicle interval timer and the normal vehicle interval timer, are both subject to reset thru plate condenser discharge by traffic actuations in the lane in which the go signal is being displayed. Hence their periods start simultaneously after each such reset. The variable vehicle interval timer is subject also to partial control by waiting cross traffic which decreases its operating period. The normal vehicle interval timer on the other hand is not affected by cross traffic.

The variable vehicle interval timer period is decreased by waiting cross traffic thru having the grid potential of the tube timing this period rendered less negative by waiting cross traffic thus causing said tube to become conducting at a lower plate voltage which correspondingly de-

creases the period required for charging the plate condenser to this lower voltage and so decreases correspondingly the variable vehicle interval. Hence the larger the amount of waiting cross traffic the shorter the variable vehicle interval will be. From the above description it can be seen that the variable vehicle interval timer in effect balances the increasing pressure to take the right of way exerted by accumulating waiting traffic on one street against the right of way retaining effect exerted by moving traffic on the other street. The latter effect may be termed the "holding power" and is proportionate to the frequency with which said moving traffic resets the variable vehicle interval timer.

If the variable vehicle interval is decreased to less than the normal vehicle interval right of way will be yielded by action of the variable vehicle interval timer when traffic ceases to approach the intersection from the lane in which the go signal is being displayed. The variable vehicle interval timer is arranged to automatically put in a return right of way call whenever it operates. If there is little waiting cross traffic and consequently the variable vehicle interval is not reduced to less than the normal vehicle interval, the normal vehicle interval timer will operate first to yield the right of way. The operation of this timer does not put in a return right of way call. Hence a right of way recall will be automatically put in if the vehicle interval at the time of right of way transfer has been reduced by waiting cross traffic to less than a predetermined period. The "predetermined period" referred to is the normal vehicle interval timer period.

If repeated traffic actuations in the lane in which the go signal is being displayed continually reset both of the vehicle interval timers thus preventing either of them from operating, the right of way will be transferred by action of the maximum timer, which is effective in the traffic timed stepping switch positions 3 or 7. A return call for the right of way is automatically put in by this timer whenever it operates.

The fact that the maximum timer operates and the normal vehicle interval timer does not operate indicates that the normal vehicle interval timer was reset by a traffic actuation less than the time period of said normal vehicle interval timer, i.e. less than a "predetermined time" before the transfer of the right of way.

The stepping switch will remain in either of its two rest positions 2 or 6 unless the system is set for normally arterial or reverting operation or unless a cross traffic call is put in by a cross lane detector actuation.

Referring to Figs. 2 and 3 the following points will be noted.

The stepping switch contact banks, designated as SB1 to SB6 inclusive, are shown in Figs. 2 and 3 to the right of the grounded power wire which extends from the bottom to the top of both figures just to the left of the center. The stepping switch driving magnet, designated as DM, is shown in the lower left corner of Fig. 3. This magnet DM drives the wipers W1 to W6 in unison over the banks SB1 to SB6 respectively. Beside it is a rectifier used to supply D. C. for the driving magnet coil.

The signals shown at the top of Fig. 2 are controlled by relays ALR and BLR. The apparatus to the left of the grounded power wire in Fig. 2 is in general effective to cooperate with the apparatus of Fig. 3 to call and hold the right of

way on the NS lane whereas that to the right of the grounded power wire similarly cooperates with the apparatus of Fig. 3 to call and hold the right of way on the EW lane.

Relay AM is energized thru contacts in stepping switch bank SB2 when the stepping switch is in positions 2 and 3, the NS rest position and the NS traffic timed positions respectively. Right of way can be called to the NS lane by the deenergization of relay AM which can occur in response to a NS traffic actuation when the right of way is not on the NS lane. Furthermore if the right of way leaves the NS lane thru action of the maximum timer relay MXR or the variable vehicle interval timer relay VVR the relay AM will be deenergized thus putting in a call for the return of the right of way to the lane from which it is being withdrawn, in this instance the NS lane. It will be remembered that the placing of a return call has been mentioned as a function of both the maximum timer and the variable vehicle interval timer.

If on the other hand the right of way is transferred from the NS lane by action of the normal vehicle interval timer relay YR, relay AM will not be deenergized but will remain locked in thru subsequent stepping switch positions unless it is deenergized by the actuation of a NS vehicle detector in order to call the right of way to the NS lane.

Relay BM performs similarly with respect to the EW lane, being operated thru contacts of stepping switch bank SB1 when the stepping switch is in position 6 or 7, the EW rest and traffic timed positions respectively. It is deenergized to put in an EW return call as the right of way is withdrawn from the EW lane if said withdrawal is caused by the maximum timer relay MXR or the variable vehicle interval timer relay VVR but remains locked in if said withdrawal of the right of way is caused by the operation of the normal vehicle interval timer relay YR. Relay BM in subsequent stepping switch positions can be deenergized by action of relay FZ in response to an actuation of EW detector Z52 in order to call the right of way to the EW lane.

Relay AR which is energized by stepping switch contacts of bank SB1 in stepping switch positions 4, 2, 3 and 4, the NS right of way and amber positions, energizes signal relay ALR and completes certain of the timing condenser circuits as will later be explained in detail.

Relay BR is energized in stepping switch positions 4, 5, 6 and 7 to similarly energize signal relay BLR and connect other timing condenser circuits.

The maximum timer, effective in the NS and EW traffic timed stepping switch positions 3 and 7 to limit the time during which moving traffic can hold the right of way against waiting cross traffic includes relay MXR, plate condenser KMX and tube MXT.

The variable vehicle interval timer includes relay VVR, tube VVT, plate condenser KVV and grid condensers KGNS and KGEW. It times the variable vehicle intervals in stepping switch positions 3 and 7, the charge in condensers KGNS and KGEW being affected respectively by EW and NS traffic so as to decrease the variable vehicle interval in the NS and EW lanes respectively in accordance with the amount of waiting cross traffic as previously mentioned.

Relay YR, tube YT and condenser KV co-

operate to time the normal vehicle interval, with the stepping switch in position 3 or 7, which interval starts simultaneously with the variable vehicle interval after each vehicle actuation in the lane having the "go" signal. The timing of the normal vehicle interval it will be remembered is not affected by waiting cross traffic whereas the timing of the variable vehicle interval is affected by waiting cross traffic.

Relay YR and tube YT cooperate with other condensers in different stepping switch positions to time other intervals as follows. The NS initial interval, stepping switch position 1, is timed by relay YR, tube YT and condenser KINS, the charge in the condenser KINS at the beginning of this interval having been predetermined by NS vehicle actuations occurring during or before the preceding display of the NS stop signal in order to time the NS initial interval in accordance with the amount of NS traffic waiting at the beginning of the NS go signal display period.

Relay YR and tube YT cooperate similarly with condenser KIEW to time the EW initial interval, stepping switch in position 5, in accordance with the amount of EW traffic waiting at the beginning of the EW go signal display period, the starting charge in condenser KIEW being predetermined in accordance with the amount of said waiting EW traffic.

The same relay and tube cooperate with condenser KY to time a minimum period during which the stepping switch remains in its rest positions 2 and 6 in order to ensure that when the go signal is given to a lane it will remain there for a reasonable minimum period. At the expiration of said minimum period the right of way will be transferred to the other lane only if traffic or normal reversion requires it, hence the name "rest position." This same group times the NS and EW amber or warning periods, stepping switch in position 4 and 8 respectively.

To more completely describe the features of the embodiment of my invention shown in Figs. 2 and 3 I shall now explain its operation thru a complete signal and stepping switch cycle beginning in the NS initial interval when the right of way has just been given to the NS lane, stepping switch in position 1.

In this stepping switch position relay AR is operated, current being supplied thru the circuit starting at grounded power thence thru position 1 of stepping switch bank SB1 to relay AR to A. C. plus power. Relay AR when operated causes signal relay ALR to be energized thru the circuit starting at A. C. plus, thru relay ALR, wire 202 to contact ar1 of relay AR thence to grounded power. Relay BR is deenergized in stepping switch position 1, its circuit being open at stepping switch bank SB2. Hence signal relay BLR is deenergized since its operating circuit includes contact br1 of relay BR.

Wipers W1 and W2 are of the bridging type so that the relays energized thru them at their respective contact banks SB1 and SB2 will not be deenergized as the stepping switch moves from one position to the next.

With relay ALR operated and relay BLR unoperated the NS go signal Z45 will be illuminated thru the circuit beginning at grounded power, thru signal Z45 thence to contact blr1 of relay BLR thence to contact ar1 of relay ALR and to A. C. plus power. The EW stop signal Z50 is illuminated thru the circuit from grounded power to A. C. plus power including signal Z50 and contact ar2 of relay ALR. The circuits to the other

four signals are incomplete in stepping switch position 1.

Explanation of the relay AM coil circuit will be helpful at this point as an aid in following this step-by-step description of the system operation.

Relay AM has an operating circuit from grounded power thru wiper W2, stepping switch bank SB2 positions 2 and 3, wire 206, 205, coil of relay AM, wires 204, 216, 217, 227, contact dm2 to A. C. plus. It has in addition a holding circuit from grounded power thru contact ez1 of relay EZ, contact am1 of relay AM, wire 205, coil of relay AM, wires 204, 216, 217 to contact am2 of relay AM, wire 219, contact mxrl of maximum timer relay MXR, contact vvr1 of variable vehicle interval timer relay VVR, thence to A. C. plus power.

In stepping switch position 2 relay AM is energized thru the operating circuit described above. That part of the operating circuit supplying current to the left side of the coil remains complete from the time the stepping switch enters position 2 until it leaves position 3 after which it is broken at bank SB2. Wiper W2 is of the bridging type to insure continuity of the above circuit as the stepping switch moves from position 2 to 3.

That part of the operating circuit energizing the right side of the coil of relay AM will be opened at contact dm2 as the stepping switch moves from position 2 to 3. However that portion of the holding circuit paralleling the last named part of the operating circuit remains intact to supply relay AM with A. C. plus power while contact dm2 is open during the stepping switch movement. From the above description it can be seen that relay AM is always energized when the stepping switch is in position 2 or 3 and when it is moving from position 2 to position 3.

The functioning of relay AM in subsequent stepping switch positions will be explained as the circuit operation in each position is considered.

The NS initial interval is timed by relay YR, tube YT and condenser KINS. During this interval condenser KINS is connected to relay YR and to the plate of tube YT thru the circuit going from grounded power to condenser KINS to wires 282, 290, 284 to stepping switch bank SB3 position 1 to wiper W3, wires 224, 225 to coil of relay YR, wire 260 to plate of tube YT. During the NS initial interval condenser KINS is charged thru the circuit starting at grounded power, to condenser KINS, wires 282, 290, 284, to stepping switch bank SB3 position 1 to wiper W3, wires 224, 223 to timing resistance RZ5, wire 214, to stepping switch bank SB4 position 1, to wiper W4, wire 226 to stepping switch driving magnet contact dm1 to D. C. plus power. When condenser KINS is charged to a predetermined voltage the tube YT will "break down," i. e. become conducting, thereby connecting relay YR to ground and allowing condenser KINS to discharge thru relay YR which will therefore operate and thru contact yr1 connect the rectifier associated with the driving magnet DM to power thus energizing the stepping switch driving magnet DM which will thereupon move the stepping switch into its next position. To vary the duration of the NS initial interval the rate at which condenser KINS is charged in stepping switch position 1 can be adjusted by regulating the variable charging resistance RZ5.

It has previously been stated that the initial interval is timed substantially in accordance with the amount of waiting cross traffic thru having the charge in the initial interval timing

condenser at the beginning of the initial interval predetermined by such waiting cross traffic. In this connection consider specifically the NS initial interval during which the stepping switch is in position 1.

While the stepping switch was last in positions 2 and 3 relay AM was energized as has been previously explained. Therefore in these two stepping switch positions condenser KINS was charged thru the circuit from grounded power to condenser KINS, wires 282, 281, contact *am4* of relay AM, to resistance RZ15, wire 228 to potentiometer resistance PZ7. The maximum voltage to which condenser KINS can be charged by this circuit is predetermined by the point on the potentiometer PZ7 to which wire 228 is attached. The rate at which condenser KINS is so charged can be regulated by the adjustment of variable resistance RZ15.

While condenser KINS was being charged in stepping switch positions 2 and 3 as explained above and during succeeding intervals up to the EW amber period immediately preceding the next NS initial interval, i. e. while the stepping switch is in positions 2, 3, 4, 5, 6 and 7, the charge of condenser KINS is subject to the removal of an increment of charge by action of condenser KZ1 at each actuation of NS detector Z51.

The fact that increments of charge are removed from condenser KINS in response to NS actuations even during the NS "go" signal display period provides a means whereby those NS vehicles which, under heavy traffic conditions, are stopped by loss of right of way after having actuated the NS detector make their presence effective to increase the next NS initial interval.

The removal of increments of charge from condenser KINS is accomplished thru the following circuit including contacts of relay EZ. Condenser KINS is connected to contact *ez2* of relay EZ thru contact *am3* of relay AM in stepping switch positions 2 and 3 and thru contact *br2* of relay BR in stepping switch positions 4, 5, 6 and 7. Hence in all of these named stepping switch positions actuations of NS detector Z51 which operates relay EZ will cause contact *ez2* and *ez3* to cooperate to remove an increment of charge from condenser KINS, such charge being transferred to condenser KZ1 by closure of contact *ez2* by each actuation and condenser KZ1 being discharged by closure of contact *ez3* between actuations.

The charge so removed from condenser KINS by waiting NS traffic is replaced thru resistance RZ5 during the initial interval thus timing said initial interval in accordance with the amount of such waiting NS traffic. When condenser KINS is so recharged, i. e. when the NS initial interval is over, tube YT becomes conductive and condenser KINS discharges thru relay YR which thereupon operates. The stepping switch, as previously explained, thereupon moves on into position 2, the NS rest position. During the movement of the stepping switch from position 1 to 2 condenser KY is discharged thru driving magnet contact *dm3* in preparation for its use as a timing condenser in stepping switch position 2.

If the system is not set for normal reversion to the EW lane and there is no waiting EW traffic the stepping switch will remain in this NS rest position and the NS lane will be continuously accorded the go signal until an EW traffic actuation shall occur.

In stepping switch position 2, the NS go signal

rest position, relay YR, tube YT and condenser KY time a predetermined minimum period at the end of which the stepping switch can be moved on into position 3 either by an EW traffic actuation or by normal reversion.

The circuit connecting relay YR, tube YT and condenser KY in stepping switch position 2 is as follows. Relay YR thru wires 225, 224, wiper W3 and position 2 of bank SB3 is connected to condenser KY thru wires 229 and 258. In addition a charging circuit is established for condenser KY starting at grounded power through condenser KY, to wires 258, 229, position 2 of bank SB3, wiper W3, wires 224, 223, adjustable resistance RZ13, wire 213, position 2 of bank SB4, wiper W4, wire 226, contact *dm1* of driving magnet DM to D. C. plus power.

Wiper W3 is of the non-bridging type so that as the stepping switch moves from one position to the next there will be no interconnection of condenser circuits. Contact *dm1* is included in the charging circuit described above to prevent the plate of tube YT from being charged to flash-over voltage during the instant that condenser KY is disconnected therefrom as wiper W3 moves from one stepping switch position to another.

The timing of the NS minimum rest position period can be adjusted by regulating resistance RZ13 to control the charging rate of condenser KY in stepping switch position 2.

The grid circuit of tube YT in stepping switch position 2 is connected thru wire 259, wiper W5 and position 2 of bank SB5, wire 291 to potentiometer PZ5. Wiper W5 is of the bridging type to prevent fluctuations in grid potential as the stepping switch moves from one position to the next.

It will be noted that the negative end of potentiometer PZ5 is permanently connected to D. C. minus but the positive end of PZ5 is connected to ground thru a circuit including wire 254 and contact *bm6* of relay BM or EW arterial switch Z69. Hence if both switch Z69 and contact *bm6* are open the potential of the grid of tube YT will be biased negative to such a degree that said tube will not break down even though plate condenser KY be charged to its maximum positive voltage. Therefore with contact *bm6* and switch Z69 open the stepping switch will remain at rest in position 2 even after condenser KY has become fully charged.

The above condition prevails if the system is not set for normal reversion to the EW lane and there is no waiting EW traffic. Under these conditions the stepping switch remains in position 2, its NS rest position, and the go signal continues to be displayed in said NS lane until the next EW traffic actuation occurs.

If normal reversion to the EW lane is desired switch Z69 is closed which will make the grid potential of tube YT less negative so that the tube will "break down" and operate relay YR thus causing the stepping switch to move from position 2 to 3 as soon as condenser KY is sufficiently charged, i. e. at the expiration of the stepping switch position 2 minimum period. If switch Z69 is not so closed the movement of the stepping switch from position 2 to 3 will take place at any time after the expiration of said minimum period upon actuation of the EW detector Z52 which will deenergize relay BM by opening its holding circuit at contact *fm1* of relay FZ. The deenergization of relay BM causes contact *bm6* to complete a circuit connecting poten-

tiometer PZ5 to ground thus making the grid potential of tube YT much less negative so as to cause the tube to "break down" and relay YR to operate, causing the stepping switch to move from position 2 to 3. If an actuation of detector Z52 takes place before the expiration of the rest position minimum period said stepping switch movement will take place at the end of this minimum period.

In stepping switch position 3 the NS go signal and the EW stop signal remain displayed and three timers, the normal vehicle interval timer, the variable vehicle interval timer and the maximum timer ran concurrently. The first two of these timers are subject to reset by NS detector actuations and the timing period of variable vehicle interval timer is in addition shortened by waiting EW traffic in accordance with the amount of such waiting EW traffic. The maximum timer is not affected by traffic in either lane and sets a maximum limit beyond which NS traffic cannot continue to hold the right of way against the cross lane.

The normal vehicle interval timer includes relay YR, tube YT and condenser KV. The grid of tube YT is in stepping switch position 3 connected to potentiometer PZ6 thru position 3 of bank SB5. The circuit from relay YR to wiper W3 of bank SB3 has been traced. Thru this bank, in position 3, condenser KV is connected to relay YR by wires 231, 232, 233 and 234.

Condenser KV, while the stepping switch was in positions 1 and 2, was being charged thru a circuit including grounded power to condenser KV, wires 234, 233, 232 and 230 to variable resistance RZ17, wire 238, contact ar4 of relay AR to positive D. C. power. In stepping switch positions 1 and 2 condenser KV was also subject to discharge by NS detector actuations thru contact ez4 of relay EZ, wire 237, contact ar2 of relay AR to ground. If, when the stepping switch enters position 3, the traffic in the NS lane has cleared the intersection condenser KV will have had sufficient time since the last NS detector actuation to become fully charged. In stepping switch position 3 condenser KV is connected to the plate of tube YT via relay YR. Hence if this condenser is fully charged when the stepping switch moves into position 3 tube YT will immediately break down and operate relay YR to move the stepping switch on into position 4 with no appreciable stop in position 3. If on the other hand NS detector actuations have recently discharged condenser KV the normal vehicle interval timer will continue its timing as long as the stepping switch remains in position 3.

The variable vehicle interval timer includes relay VVR, tube VVT, plate condenser KVV and, in stepping switch position 3, grid condenser KGNS. In stepping switch position 3 plate condenser KVV is charged thru a circuit from grounded power to condenser KVV, wire 263, 261, 222, 221, 220, variable resistance RZ4, wire 212 to position 3 of bank SB4, wiper W4, wire 226, contact dm1 to D. C. plus power. Wiper W4 is of the non-bridging type to prevent interconnection of charging circuits during stepping switch movement. Contact dm1 is included in this circuit to prevent tube flashover during the stepping switch movement as has been explained before.

Condenser KVV is subject to discharge upon actuation of NS detector Z51 thru circuit from the tap wire 311 on potentiometer PZ7 via wire 350 to contact ar6 of relay AR to contact ez5 of re-

lay EZ thru wire 240 which ties into the condenser KVV charging circuit at wire 222. The grid of tube VVT is connected to condenser KGNS thru the circuit including wire 249, contact br5 of relay BR and wire 246 to condenser KGNS, thence to ground. The charge of condenser KGNS has in previous stepping switch positions been made less negative by the removal of increments of charge by condenser KBNS, one increment of charge being removed for each actuation of EW detector Z52, so that the charge on condenser KGNS when the stepping switch is in position 3 has been reduced in accordance with the amount of waiting EW traffic.

The circuits which accomplish the above results are as follows: In stepping switch positions 6 and 7 condenser KGNS is charged negatively thru the circuit from grounded power to condenser KGNS, wires 246, 247, contact bm5, variable resistor RZ20, wire 255 to potentiometer PZ6. The point at which wire 255 makes contact with potentiometer PZ6 fixes the maximum negative potential to which condenser KGNS can be charged by this circuit. The rate at which this charge takes place can be regulated by adjusting resistance RZ20.

The removal of increments of charge from the condenser KGNS is accomplished as follows. In all stepping switch positions condenser KBNS is charged by condenser KGNS and then discharged to a predetermined potential once for each actuation of EW detector Z52. This detector operates relay FZ whose contacts fz6 and fz7 are effective to accomplish the above as follows. With contact fz7 closed condenser KBNS is discharged to a predetermined voltage thru the circuit including grounded power, condenser KBNS, wire 248, contact fz7, wire 250 to potentiometer PZ6. The voltage to which condenser KBNS is so discharged is regulated by setting the point at which wire 250 contacts potentiometer PZ6. A vehicle actuation of EW detector Z52 opens this discharge circuit at contact fz7 and connects condenser KBNS to condenser KGNS thru the direct circuit including contact fz6. The voltage on condenser KBNS, which was regulated to be less negative than that of condenser KGNS, will therefore cause the voltage on condenser KGNS to become less negative. Hence, when the stepping switch reaches position 3 the charge in condenser KGNS will have been reduced in accordance with the total of all the increments removed by condenser KBNS in response to EW traffic actuations and substantially in accordance with the number of such EW actuations since the right of way last left the EW lane.

The fact that increments of charge are removed from condenser KGNS in response to EW traffic actuations even during the EW go signal display period provides a means whereby those EW vehicles which, under heavy traffic conditions, are stopped by loss of the right of way after having actuated the EW detector make their presence felt in decreasing the next NS variable vehicle interval timing by means which will now be explained.

Since condenser KGNS in stepping switch position 3 acts as the grid condenser for tube VVT of the variable vehicle interval timer it follows that the time required for the plate condenser KVV to be charged to a voltage sufficient to cause tube VVT to break down, i. e. the variable vehicle interval, will be decreased substantially in ac-

cordance with the reduction of negative charge in condenser KGNS hence substantially in accordance with the amount of waiting EW traffic.

When tube VVT does break down condenser KVV will discharge thru this tube and relay VVR thus energizing the driving magnet rectifier thru contact *vvrl* and so move the stepping switch on into position 4. At the same time, thru the opening of contact *vvrl* and thru the opening of contact *dm2*, which is opened by the operation of the driving magnet DM, both circuits which have previously been traced to the right side of the coil of relay AM are opened. Therefore relay AM will be released to put in a return right of way call.

When the variable vehicle interval relay VVR so acts to cause the stepping switch movement into position 4, it is obvious that its period had been reduced by waiting cross traffic to less than that of the normal vehicle interval timer. Hence the right of way return call put in by relay VVR is occasioned by the reduction of the variable vehicle interval by cross traffic to "less than a predetermined time."

If NS traffic is heavy and NS detector actuations repeatedly reset the normal vehicle interval time and the variable vehicle interval timer, the maximum timer will after a predetermined time act to move the stepping switch into position 4 and so transfer the right of way from the NS lane. The maximum timer consists of relay MXR, tube MXT and plate condenser KMX. In stepping switch position 3 condenser KMX is charged by a circuit from grounded power to condenser KMX, wire 268, thru variable resistance RZ2 to position 3 of bank SB6 thence thru wiper W6 to D. C. plus power. The timing of the maximum period can be regulated by varying resistance RZ2. When condenser KMX reaches a predetermined voltage tube MXT will break down and operate relay MXR by discharging condenser KMX thru the circuit from grounded power thru condenser KMX, wires 268, 269, coil of relay MXR, tube MXT, to ground.

The operation of relay MXR causes the stepping switch driving magnet rectifier to be energized thru contact *mxr2* and so moves the stepping switch into position 4. At the same time, thru the operation of contacts *mxr1* and *dm2* both circuits previously traced to the right side of the coil of relay AM are opened. Relay AM is therefore deenergized to put in a NS right of way return call. The fact that the transfer of the right of way was occasioned by the operation of the maximum timer relay MXR rather than by action of the normal vehicle interval timer indicates that a NS detector had been actuated less than the operating period of the normal vehicle interval timer, i. e. "less than a predetermined time", previous to said transfer of the right of way, which condition it will be remembered is one under which a return right of way call is put in by this apparatus.

The deenergization of relay AM causes the return of the right of way to the NS lane by moving the stepping switch out of the EW rest position 6. This is accomplished as follows.

When relay AM is deenergized back contact *am6* closes and connects the left terminal of potentiometer PZ4 to grounded power. When the stepping switch next reaches position 6 this will cause the grid potential of tube YT, which in this stepping switch position is connected to potentiometer PZ4 thru wire 259, wiper W5 and position 6 of bank SB5 and wire 357, to become

less negative thereby permitting tube YT to become conductive when its plate condenser KY has been charged to a sufficient voltage. Condenser KY will thereupon discharge thru relay YR and so operate relay YR which will cause the driving magnet to move the stepping switch on into position 7. This operation was discussed in connection with the operation of the equivalent timing circuit when the stepping switch was in the NS rest position 2.

As the stepping switch moves from position 3 to 4 condenser KY is discharged thru driving magnet contact *dm3*, condenser KVV is discharged thru contact *dm4* and condenser KMX is discharged thru contact *dm5* to prepare them for timing their next intervals.

In stepping switch position 4 the NS go signal is extinguished and the NS amber signal is illuminated. To accomplish this change relay BR is energized thru wiper W2 and position 4 of bank SB2. Contact *blr1* of relay BR being thereby closed light relay BLR is operated which extinguishes the NS go signal Z45 by opening contact *blr1* and illuminates the NS amber signal Z46 by closure of the contact *blr2*.

While the warning or stop signal is being displayed in the NS lane, stepping switch in position 4, 5, 6, 7 or 8, relay AM, as previously explained, depends for its current on a holding circuit which includes contact *ez1* of relay EZ. Therefore thru the opening of contact *ez1* relay AM will be deenergized by a NS vehicle actuation occurring during the NS warning or stop signal display period. Relay AM will thereupon function to call the right of way to the NS lane in the manner previously explained.

The NS amber or warning period, stepping switch in position 4 is timed by relay YR, tube YT and condenser KY which is connected to plate circuit of tube YT thru relay YR and wiper W3 and position 4 of bank SB3.

Condenser KY is charged during this period thru a circuit from grounded power to condenser KY, wires 258, 229, position 4 and wiper W3 of bank SB3, wire 224, 223, variable resistance RZ1, wire 211, position 4 and wiper W4 of bank SB4, wire 226, contact *dm1* to D. C. plus. The duration of the NS amber period can be regulated by adjusting resistance RZ1 to control the charging rate of condenser KY during this period. The grid of tube YT is connected to potentiometer PZ6. When condenser KY is charged to a predetermined voltage tube YT will become conductive and discharge the energy of condenser KY thru relay YR thus operating the driving magnet DM to move the stepping switch into position 5.

Stepping switch positions 5, 6, 7 and 8 correspond respectively to positions 1, 2, 3 and 4 except that the go signal or the amber signal is being displayed to the EW lane instead of the NS lane and the functions of the NS and EW detectors are in general interchanged so that EW actuations tend to extend the timing periods while the NS actuations tend to decrease them.

In stepping switch position 5 relay AR is unoperated hence the NS stop signal Z47 is illuminated thru contact *alr1* and the EW go signal Z48 is illuminated thru contacts *blr4* and *alr3*. The EW stop signal Z50 is extinguished by the opening of contact *alr2*.

The EW initial interval, stepping switch in position 5, is timed by relay YR, tube YT and condenser KIEW just as the NS initial interval is timed by the same relay and tube cooperating with condenser KINS. Condenser KIEW has

been prepared for timing the EW initial interval in accordance with the waiting EW traffic by having its initial charge, introduced during the last EW go signal period thru contact *bm4* and resistance *RZ16*, decreased during and subsequent to this charging period by the removal of charge increments by condenser *KZ2* in response to EW actuations, just as condenser *KINS* was prepared to time the NS initial interval.

The removal of increments of charge from condenser *KIEW* by condenser *KZ2* is accomplished thru contacts *fz2* and *fz3* of relay *FZ*. During the EW initial interval condenser *KIEW* is recharged thru the circuit from ground to condenser *KIEW*, wire *283*, position *5* and wiper *W3* of bank *SB3*, wires *224*, *223*, *210*, variable resistance *RZ10*, wire *215*, position *5* and wiper *W4* of bank *SB4*, wire *226* and contact *dm1* to D. C. plus power. At the end of the EW initial interval, condenser *KIEW* having been recharged, tube *YT* becomes conducting and permits condenser *KIEW* to discharge thru wire *283*, position *5* and wiper *W3* of bank *SB3*, wires *224*, *225*, coil of relay *YR* and tube *YT* to ground. Relay *YR* thereupon operates and the stepping switch moves on into position *6*, the EW rest position.

When the stepping switch is in position *6* relay *BM* is operated. The circuits and functions of this relay are similar to those of relay *AM* except that they apply in general to the EW lane instead of the NS lane. It has an operating circuit from grounded power thru wiper *W1* and position *6* of bank *SB1*, wires *209*, *208*, coil of relay *BM*, wires *207*, *276*, *277*, *227*, contact *dm2* to A. C. plus power. When relay *BM* operates an additional source of A. C. plus power thru a holding circuit independent of contact *dm2* is connected to the left side of the coil of relay *BM* thru wire *207*, *276*, *278*, contact *bm2*, wire *219*, contact *mxr1* and contact *vrl1* to A. C. plus power.

When relay *BM* operates an additional source of grounded power is connected to the right side of the coil of relay *BM* thru wire *208*, contact *bm1* and *fz1* thence to grounded power. These last two described additional circuits taken together constitute a holding circuit similar to that previously described in connection with relay *AM*. The conditions under which this holding circuit will be broken to deenergize relay *BM* and so call the right of way to the EW lane are similar to those effective in the case of the corresponding holding circuit associated with relay *AM* and will be described in detail later.

In stepping switch position *6*, the EW rest position, relay *YR*, tube *YT* and condenser *KY* cooperate to time a minimum period at the expiration of which the stepping switch can be moved on into position *7* by normal reversion if NS arterial switch *Z68* is closed or by an actuation of NS detector *Z51* just as it is moved into position *4* if switch *Z69* is closed or EW detector *Z52* is actuated. In stepping switch position *6* the timing circuit is substantially the same as that effective in position *2* except that condenser *KY* is charged thru variable resistance *RZ14* instead of variable resistance *RZ13* and that the grid of tube *YT* is connected to potentiometer *PZ4* instead of *PZ5* thereby making the movement of the stepping switch out of position *6* dependent upon NS arterial switch *Z68* or NS traffic thru deenergization of relay *AM* instead of EW arterial switch *Z69* or EW traffic deenergization of relay *BM*.

In stepping switch position *7*, the EW traffic timed position, the normal vehicle interval timer, the variable vehicle interval timer and the maximum

timer, run concurrently just as they did in the corresponding stepping switch position *3*, the NS traffic timed position. The charging circuit for condenser *KV* of the normal vehicle interval timer in stepping switch position *7* includes variable resistance *RZ18* instead of variable resistance *RZ17* which was in this circuit in stepping switch position *3*. Likewise in the variable vehicle interval timer condenser *KVV* charging circuit resistance *RZ9* replaces the corresponding resistance *RZ4* and in the maximum timer condenser *KMX* charging circuit resistance *RZ1* replaces the corresponding resistance *RZ2*. The substitution of these resistances permits the timing of the corresponding NS and EW intervals to be independently adjusted.

In stepping switch position *7* condenser *KGEW* is included in the grid circuit of variable vehicle interval timer tube *VVT* in place of condenser *KGNS* which was attached to the grid of tube *VVT* in stepping switch position *3*. Grid condenser *KGEW*, while the stepping switch is in NS go positions *2* and *3*, is charged negatively thru the circuit from grounded power to condenser *KGEW*, wires *245*, *244*, contact *am5*, variable resistance *RZ19*, wire *256* to potentiometer resistance *PZ6*.

During and subsequently to the above charging period the negative charge in condenser *KGEW* is decreased by the withdrawal of an increment of charge by condenser *KBEW* thru the operation of contacts *ez6* and *ez7* of relay *EZ*, at each NS detector actuation in order to decrease the EW variable vehicle interval in accordance with the amount of waiting NS traffic just as the NS variable vehicle interval was decreased in accordance with the amount of waiting EW traffic thru the removal of negative charges from condenser *KGNS* by condenser *KBNS* thru contacts *fz6* and *fz7* which has been previously explained.

As the stepping switch leaves position *7*, if this movement is occasioned by variable vehicle interval timer relay *VVR* or by maximum timer relay *MXR*, relay *BM* will be deenergized to put in a call for the return of the right of way to the EW lane just as relay *AM* was deenergized if either of these relays moved the stepping switch from position *3* to *4*, which has previously been described. This deenergization of relay *BM* will result from the removal of A. C. plus power connections from its coil thru the opening of its holding circuit at contact *vrl1* of relay *VVR* or contact *mxr1* of relay *MXR* and the opening of its operating circuit at contact *dm2*, both of which circuits have been traced from A. C. plus power to the left side of the coil of relay *BM*.

If the stepping switch movement from position *7* to *8* is on the other hand occasioned by the operation of the normal vehicle interval timer relay *YR* relay *BM* will not be deenergized and hence no EW return right of way call will be put in.

In those stepping switch positions in which the warning signal or the stop signal is being displayed to the EW lane that part of the relay *BM* operating circuit including bank *SB1* is open at this bank and the previously described parallel holding circuit including contact *fz1* of relay *FZ* and *bm1* of relay *BM* becomes the sole supply of current to the right side of the coil of relay *BM*. The first EW detector actuation during the EW stop or warning signal display period will open this holding circuit at contact *fz1* and deenergize relay *BM* thereby putting in a call for the return of the right of way to the EW lane. Said return of the right of way will be occasioned by back

contact *bm6* of relay *BM* completing to ground the power the circuit of potentiometer *PZ5* thus when the stepping switch next reaches the *NS* rest position *2* making less negative the potential of the grid of tube *YT* so that tube *YT* will break down when its plate condenser becomes sufficiently charged and operate relay *YR* to carry the stepping switch out of the said *NS* rest position.

Stepping switch position *8* is the *EW* amber or warning period position. Relay *BR* is energized in this position thus deenergizing light relay, *BLR* also. Since relays *AR* and *ALR* are also deenergized in this stepping switch position the *EW* go signal *Z48* will be extinguished by the opening of contact *blr4* and the *EW* amber signal *Z49* will be illuminated thru the closure of contact *blr3*.

The duration of the *EW* amber period is timed by relay *YR*, tube *YT* and condenser *KY* just as the *NS* amber period was timed by them except that condenser charging resistance *RZ6* replaces resistance *RZ1* so that the timing of the *EW* and *NS* amber periods can be independently adjusted. When relay *YR* operates, driving magnet *DM* moves the stepping switch into position *1* at the same time discharging condenser *KY* thru contact *dm3* to prepare it for timing subsequent intervals. This completes the signal display cycle.

To summarize briefly, intervals are timed as follows by the apparatus of the embodiment of my invention shown in Figs. 2 and 3.

The *NS* initial interval, stepping switch in position *1*, is timed by regular charging of condenser *KINS* which has previously been subject to the removal of unit charges by *NS* traffic actuators. The replacement of these removed charges times this period in accordance with the amount of such waiting *NS* traffic.

The *EW* initial interval, stepping switch in position *5*, is timed similarly by condenser *KIEW* from which unit charges have previously been removed by *EW* traffic.

The *NS* traffic timed right of way period, stepping switch in position *3*, is timed concurrently by three timers, the normal vehicle interval timer, the variable vehicle interval timer, and the maximum timer.

The *NS* normal vehicle interval is timed by regular charging of condenser *KV* subject to reset discharge by *NS* traffic actuators. This condenser is being so charged and discharged in stepping switch position *2*, the *NS* rest position, so that the normal vehicle interval timer will be effective to move the stepping switch out of position *3* into position *4* thus transferring the right of way without delay if all *NS* traffic has cleared the intersection when the stepping switch moves into position *3*.

The *NS* variable vehicle interval is timed by regular charging of condenser *KVV* which, in stepping switch position *3*, is subject to reset discharge by *NS* traffic actuators. At the same time the period of the variable vehicle interval timer is governed by the charge in condenser *KGNS* which has been previously regulated in accordance with *EW* traffic actuators.

The *EW* traffic timed right of way period, stepping switch in position *7*, is similarly timed by the same three timers. However, in the variable vehicle interval timer condenser *KGEW* replaces condenser *KGNS* so that the period of the variable vehicle interval timer when timing the *EW* lane will be governed by waiting *NS* traffic.

Now considering the present invention as ap-

plied to one embodiment of the aforesaid copending application, two additional gas discharge tubes *DT* and *ET* of the grid controlled type similar to tube *VVT* are connected with the anodes and cathodes in parallel with the anode and cathode respectively of tube *VVT*, so that tubes *DT* and *ET* each serve in addition to tube *VVT* as elements responsive to a particular level of charge and corresponding voltage on condenser *KVV* in timing the variable vehicle interval.

As will now be explained each tube has its grid bias individually adjusted in accordance with certain traffic or other conditions to determine the level of charge on condenser *KVV* at which the anode-cathode circuit of the tube will become conducting to operate relay *VVR* by discharge of condenser *KVV*, and thus to operate stepping magnet *DM* and step the stepping switch from the right of way position for the lane for which the variable vehicle interval or "traffic timed interval" is being timed. Since all three tubes *VVT*, *DT*, and *ET* are connected to be controlled by condenser *KVV* to operate relay *VVR*, whichever tube has its grid bias adjusted to the lowest value to make its break down voltage for conduction lowest will become conducting to operate relay *VVR*, as the voltage on condenser *KVV* increases progressively in its timing action.

The grid bias of tube *VVT* is reduced progressively by a small amount for each of a series of actuations by traffic arriving (and waiting) against a stop signal as described above, and this is one of the features of the copending application.

The grid bias of tube *DT* is reduced progressively by a small amount for each of a series of actuations by traffic moving with the go signal, in accordance with one feature of the present invention, these latter actuations being the same traffic actuations which momentarily discharge condenser *KVV* to reset its timing action to prolong the go signal period. Between such actuations the grid bias of tube *DT* is increased gradually, tending to restore it to the original value it had before the reduction in bias by actuations.

Since reduction of the grid bias reduces the break down voltage for the anode-cathode circuit of the tube, the latter will become conducting to operate relay *VVR* at a lower level of charge on timing condenser *KVV* and thus will reduce the variable vehicle interval timed by the gradual recharging of condenser *KVV* from each actuation by traffic having right of way. Thus the right of way will be terminated on occurrence of a smaller time gap between vehicles than would have been initially the case before such reduction of grid bias.

The reduction of grid bias on tube *DT* by traffic moving on the go signal is provided as follows. Assume that the stepping switch is in the *NS* traffic timed position *3* in which the green signal is displayed to *NS* and the red signal is displayed to *EW*, and in which relay *AR* (Fig. 2) is in energized position and relay *BR* is in deenergized position. In this position the grid of tube *DT* has initially a relatively high bias provided by its connection via small limiting resistance *RX2*, wires *319*, *348*, contact *br7* of relay *BR*, wire *317*, control resistance *RZ21*, wire *321* to potentiometer *PZ6*. Condenser *KD* is connected via resistance *RX2* and wire *319* between the grid of tube *DT* and the ground wire, to

which the cathode of tube DT is also connected, and serves to control the grid bias potential.

This condenser is of large capacity (of the order of 5 mfd. for example). Upon actuation of the NS traffic detector Z51 in position 3 of the stepping switch the relay EZ will be energized momentarily and at its contact ez8 will connect a small condenser KDNS1 for example to condenser KD to reduce the charge and negative potential in condenser KD by a small increment. This occurs by circuit from ground wire via wire 345, condenser KDNS1, wire 315, limiting resistance RX3, contact ez8, wires 316, 317, contact br7, wire 348, condenser KD to ground wire.

Relay EZ is deenergized again after each momentary actuation and in its deenergized position via contact ez9 connects condenser KDNS1 via wire 313 to a point on potentiometer PZ6 nearer ground to discharge condenser KDNS1. Thus with each traffic actuation a small increment of charge is removed from condenser KD by small condenser KDNS1. This reduces the bias potential of the grid of tube DT and makes the later responsive to a lower potential on the main variable vehicle interval timing condenser KVV.

Between such actuations the circuit from condenser KD via the control resistance RZ21 to a high negative point on potentiometer PZ6 will gradually recharge condenser KD at a relatively slow time rate proportional to capacity of condenser KD and inversely proportional to the size of resistance RZ21 and thus will tend to restore the grid bias on tube DT to its initial value.

An auxiliary condenser KDNS2 similar to KDNS1 is provided for connection in parallel with KDNS1 by switch 343 to increase the increment of charge removed from condenser KD with each traffic actuation if desired. Switch 343 is set in one position or the other manually to balance the actuation effect on the grid bias for two and four lane streets, for example. A similar arrangement may be used to provide adjustable capacity for condensers KBNS and KBEW for example, and is useful in compensating for differences in the number of non-interfering lanes receiving right of way simultaneously at different types of street intersections.

With the stepping switch in the EW traffic timed position 7 in which the green signal is displayed to EW and the red signal to NS, relay AR is in its deenergized position and relay BR is in energized position, and the grid of tube DT is connected via resistance RX2 and wire 319 to condenser KD as before but is now disconnected from the lower contact br7 of relay BR and is connected with the upper contact br6 to place the grid under control of EW traffic. EW traffic actuations momentarily energize relay FZ and at contact fz8 remove small charges from condenser KD by means of the small condenser KDEW1. Each energization of relay FZ disconnects condenser KDEW1 from wire 314 connecting with low point on potentiometer PZ6, and connects KDEW1 with condenser KD via the limiting resistance RX4, contact fz8, contact br6, and wire 348 to remove a small charge from condenser KD. Successive actuations will successively reduce the charge on condenser KD and thus successively reduce the grid bias and reduce the EW vehicle interval correspondingly. In the absence of EW actuation and between EW actuations condenser KD in position 7 of the stepping switch is connected via wire 348 and contact 75

br6 and control resistance RZ22 and wire 320 to a high bias point on the potentiometer PZ6.

In accordance with another feature of the present invention the grid bias of another tube ET is reduced at a slow time rate to reduce the vehicle interval gradually during the right of way period. In the preferred arrangement with switches 338 and 334 closed as shown in Fig. 3, this slow reduction of the grid bias to reduce the vehicle interval is under control of the respective relays AM and BM which are released responsive to traffic approaching a red signal and begins with the arrival of the first vehicle to wait against the stop signal on the street not having right of way. In an alternative arrangement which may be desirable in some circumstances, one or the other or both switches 334 and 338 may be set in their open position and the timed gradual reduction of the grid bias of tube ET and the consequent reduction of the vehicle interval will proceed throughout the right of way period without waiting for the first vehicle to arrive against a red signal. With only switch 338 open the timed reduction of the EW vehicle interval starts automatically at the beginning of the EW green period and timed reduction of the NS vehicle interval is dependent upon EW vehicle actuation. With only switch 334 open the timed reduction of the NS vehicle interval starts automatically with NS green but timed reduction of the EW vehicle interval is dependent on NS vehicle actuation. With both switches open the timed reduction of vehicle interval on each street will start automatically 35 with the green on that street.

The timed reduction of grid bias of tube ET is provided as follows. Condenser KE is connected between ground and the grid of tube ET via limiting resistance RX5. Condenser KE controls the grid potential of tube ET in connection with one or another of the control resistances RZ23 and RZ24 and its capacity is selected with respect to these high resistances to serve as a timing condenser in controlling grid voltage bias reduction. In the NS vehicle interval position 3 of the stepping switch, relay AR is energized and relay BR is deenergized. Assume switches 338 and 334 closed as shown in Fig. 3, and assume that no traffic is yet waiting on the EW street, and relay BM is therefore energized as described above. Then condenser KE and the grid of tube ET are connected via limiting resistance RX5, wire 325, contact br9 of relay BR, contact bm7, wires 335 and 336 to a high bias point on potentiometer PZ6 which maintains the grid at its initial bias.

Now if an EW vehicle arrives, and starts waiting against the red signal being displayed to the EW street, the relay BM will be deenergized and will remain deenergized since its original operating circuit is open and its lock in circuit is now also open as described above. The contact bm7 will now therefore be open and the connection of the grid and condenser KE with the high bias point on the potentiometer PZ6 will be interrupted, thus rendering effective the branch circuit from condenser KE and the grid via br9, wire 332, control resistance RZ24 and wire 340 to a relatively low bias point on potentiometer PZ6. This allows condenser KE to discharge slowly at a time rate determined by the control resistance RZ24, and thus gradually reduces the grid bias of tube ET and correspondingly reduces the NS vehicle interval which determines the maximum limiting gap in traffic at which NS

traffic will yield right of way to the waiting EW traffic. Since the timed slow reduction of the grid bias of tube ET for the NS vehicle interval was initiated by the arrival of the first waiting vehicle on EW, and proceeds at a predetermined time rate in accordance with the well known discharge characteristic of a condenser, the consequent reduction in the NS vehicle interval is substantially in accordance with the length of time any EW traffic has been waiting for right of way.

After termination of NS right of way and shift of the stepping switch to NS amber position 4, relay AR remains energized and relay BR becomes energized as will be noted by reference to banks SB1 and SB2 of the stepping switch. In this position the grid control condenser KE is restored to a high bias voltage again as a starting point for control of the EW vehicle interval in the following EW right of way period, this restoration being accomplished by connection of condenser KE via wire 325, contact br8, wire 328, contact ar9, and wire 337 to a high bias point on potentiometer PZ6.

In the EW traffic time interval, stepping switch position 7, the relay AR is deenergized and relay BR is energized, and the grid control condenser KE is connected via wire 325, contact br8, wires 326, 327, and control resistance RZ23 and wire 341 to a low point on potentiometer PZ6. Assuming switch 338 closed as shown in Fig. 3, the circuit just described is ineffective in absence of NS traffic actuation since it is shunted by a circuit via wire 328, 329, switch 338, contact am1, and wire 337 to a high point on potentiometer PZ6. Upon NS traffic actuation however, relay AM is deenergized and remains deenergized as described above, and contact am1 opens to interrupt the shunting circuit and thus permit condenser KE to discharge slowly at its characteristic time rate through control resistance RZ23. As condenser KE gradually discharges during the EW right of way period the EW vehicle interval is reduced correspondingly in a manner similar to that described in connection with the NS vehicle interval reduction.

Fig. 4 shows the condenser KD and tube DT and associated apparatus provided in accordance with the feature of the present invention of reducing the vehicle interval or gap limit interval by closely spaced traffic having the right of way, or by what might be termed the volume or density of traffic having right of way. In this figure the tube VVT and associated grid control condensers KGNS and KGEW and unit charge removing condensers KBNS and KBEW are omitted, as are also the tube ET and grid control condenser KE and associated circuits. Fig. 4 should be viewed in conjunction with Figs. 2 and 3, except for the apparatus which may be omitted or disregarded as above noted, for the purpose of considering a complete cycle of operation of the apparatus as part of a right of way traffic control system, but Fig. 4 illustrates particularly the apparatus and circuits providing reduction of the vehicle interval for right of way by traffic having the right of way as one of the features of the present invention, together with repetition of certain elements and circuits common with Fig. 3 and with the disclosure of the copending application, such as the vehicle interval timing condenser KVV and traffic actuated reset circuits via contacts e25 and f25 therefor, the VVR relay coil, and the stepping switch bank SB4 which connects the charging circuits via control resistances RZ4 and RZ9 to condenser

KVV to time the vehicle interval in the NS and EW traffic timed positions of the stepping switch cycle. The potentiometer PZ6—PZ1 and the circuit via contact dm4 for resetting condenser KVV in stepping from one position to the next by action of stepping magnet DM are also repeated from Fig. 3, and it will be understood that in the traffic timed positions 3 and 1 the operation of relay VVR by discharge of condenser KVV through tube DT upon completion of vehicle interval timing during a gap in traffic will energize stepping magnet DM and step the stepping switch wipers to the next position to continue operation of the signal cycle, as described above in connection with Figs. 2 and 3.

It is believed that reference to Fig. 4 in connection with the preceding description of operation of the grid control of the grid of tube DT by condenser KD and the related circuits will assist in an understanding of the novelty of this feature of the invention and will serve to illustrate how these features may be employed alone to reduce the vehicle interval if desired, without the feature of the copending application of reduction in accordance with amount of traffic waiting as provided by tube VVT, and without the feature of the present invention of the reduction of the vehicle interval in accordance with the length of time of right of way or of traffic waiting.

The apparatus particularly concerned with the last mentioned feature is shown in Fig. 5, which like Fig. 4, also repeats certain of the other common apparatus from Fig. 3 to permit the complete operation of the vehicle interval timing device to be viewed separately as controlled by the timing action of condenser KE on the reduction of grid bias of tube ET. It is believed that Fig. 5 will assist in an understanding of the individual novelty of this latter feature of the invention.

The reference legends and general layout of the parts of Figs. 4 and 5 are the same as that of the corresponding parts of Figs. 2 and 3 so that the operation of the parts and circuits can readily be followed by reference to the description of the corresponding parts of Figs. 2-3.

It will be understood that insofar as the features of the invention illustrated in Figs. 4 and 5 are concerned it is not essential that the initial interval be varied in accordance with the amount of traffic waiting as described above in connection with Figs. 2 and 3 and that a predetermined initial interval might be employed for each street for example or the initial interval might be omitted entirely as a separate part of the cycle by making the reduction of the vehicle interval in accordance with one or another feature of the invention quite extensive, starting with a sufficiently long vehicle interval at the beginning of the right of way period to serve to permit standing traffic to get into motion, and then reducing this vehicle interval progressively at a rather rapid rate early in the right of way timing period by the vehicle interval timer, with a slower reduction as the right of way period is prolonged progressively by moving traffic, along the lines of the tapering off of the discharge curve of the grid control condensers. In applying the invention in this manner however the vehicle detectors would preferably be set nearer to the intersection for most efficient results.

In the preferred embodiment of my invention however the initial interval is preferably automatically varied in accordance with amount of

waiting traffic as described in connection with Figs. 2 and 3, for improved efficiency of operation.

The present invention may be employed with advantage in combination with the apparatus of the copending application to obtain a marked coordination of timing of the signals at a series of intersections along a street or through a group of intersections forming a grid of which a small part is illustrated in Fig. 6 for example, without interconnection or forced resynchronization of any kind. The feature of the reduction of vehicle interval in accordance with the density of moving traffic having the right of way as illustrated in Fig. 4 is of particular advantage in this regard in combination with the feature of reduction of vehicle interval in accordance with the amount of traffic arriving against a red signal. If it is desired to emphasize this coordination effect the traffic detectors are preferably set back further from the intersection than would be the case for control of the intersection as an isolated unit, in order to enable the control mechanism to reduce the vehicle interval in accordance with the approach of a considerable group or fleet of vehicles against the red signal before any considerable part of such group reaches the intersection and is required to stop.

With proper spacing of signalized intersections and traffic speed in relation thereto the traffic may be organized into fleets of vehicles traveling through the series of intersections progressively with the green signal periods appearing to travel along the street in either direction, the gaps appearing between fleets of vehicles matching the red periods on the common street to permit the cross streets to receive the green signal.

The apparatus of Fig. 4 aids in recognizing promptly the end of the main fleet of vehicles in any group since the closely spaced vehicles in the fleet will progressively reduce the vehicle interval setting a gap limit progressively closer to the actual gap between vehicles in the fleet and as soon as the main fleet has passed, the spacing of vehicles will increase rather rapidly and the right of way will be terminated promptly and transferred to traffic on the cross street.

In the combined apparatus of Figs. 2 and 3 it may be desirable in certain instances to reduce the vehicle interval almost to zero in order to prevent traffic practically from holding right of way any longer against opposing traffic, in place of a separate overall maximum right of way timing circuit and tube and condenser for example, or responsive to a preferred vehicle such as a street railway car for example by means of a separate relay corresponding to AM or BM for actuation by such vehicle to connect condenser KE effectively through a relatively low resistance to a very low bias point on potentiometer PZ6.

For the purpose of permitting such drastic reduction of the vehicle interval either rapidly or gradually, when desired, the present embodiment resets the vehicle interval timing action by discharging the condenser KVV to a predetermined value considerably above complete discharge and determined by the tap 311 on potentiometer PZ7 and wire 312 connecting with the ballast condenser KX. The stepping switch magnet DM resets condenser KVV by contact *dm4* and a limiting resistance and the connection with condenser KX and the tap 311 on potentiometer PZ7, and the traffic actuated reset of condenser KVV to prolong right of way is connected via contact *ez5* and contact *ar6* or via contact *ez5* and contact *ar7*, through wire 350 to the tap 311.

In my preferred embodiment I have found it satisfactory to employ a total D. C. voltage of about 450, that is across PZ7 and PZ6 together as one potentiometer, with about 400 volts on PZ7 and about 50 volts on PZ6 which serves to control the negative bias voltage on the grids of tubes VVT, YT, DT, and ET. For these tubes I have found an operating range of about 100 to 400 volts satisfactory on the anode-cathode circuits and a ratio of break-down voltage to grid bias of about 10 to 1. The timing and grid control condensers KV, KY, KMX, KINS, KIEW, KGNS, KGEW, KVV, KD, and KE may preferably be of 5 mfd. capacity and the control resistances of the order of 200,000 ohms per second of time desired, for example. The condensers KBNS, KBEW, KZ1, KZ2, KDNS1, KDNS2, KDEW1, and KDEW2, may preferably be of the order of 0.1 to 0.4 mfd., the capacity of these condensers depending upon the number of parallel traffic lanes on the streets and the degree of effect desired to be obtained for each traffic actuation in connection with the several circuits for removing charges from the main condensers by small unit charges responsive to traffic actuations.

It will be appreciated that while the apparatus disclosed represents preferred embodiments of my invention considerable modification may be made in the values of the electrical elements, in the design and arrangement of the several parts and substitution of equivalent parts and circuits by those skilled in the art without departing from the spirit of the invention as defined by the claims.

I claim:

1. In a traffic control apparatus for according right of way successively to each of a plurality of interfering traffic lanes, means responsive to each of a plurality of traffic units in one lane during right of way accord therein to prolong such right of way for a small increment of time, and further means to reduce the length of said increment responsive to closely spaced such traffic units.
2. In a traffic control apparatus for according right of way successively to each of a plurality of interfering traffic lanes, means responsive to each of a plurality of traffic units in one lane during right of way accord therein to prolong such right of way for a small increment of time, and further means responsive to such traffic units in said one lane to adjust the length of said increment substantially in accordance with the time spacing between such traffic units.
3. In a traffic control apparatus for according right of way successively to each of a plurality of interfering traffic lanes, means responsive to each of a plurality of traffic units in one lane during right of way accord therein to prolong such right of way for a small increment of time, and means responsive to traffic in another of said lanes during right of way accord in said one lane to reduce said increment gradually in accordance with the length of time such traffic in said other lane has been waiting for accord of right of way.
4. In a traffic control apparatus for according right of way successively to each of a plurality of interfering traffic lanes and having means responsive to each of a plurality of traffic units in one lane during right of way accord therein to prolong such right of way for a small increment of time, the combination of three concurrently acting timing means for timing independently adjustable time intervals for determining the

length of said increment of right of way prolongation, the first such means acting to reduce its time interval progressively responsive to the number of units of traffic on another of said lanes waiting for right of way, the second such 5 means acting to reduce its time interval gradually responsive to the length of time any traffic has been waiting for right of way on said other lane, and the third such means acting to reduce its time interval responsive to close spacing of moving traffic units in said one lane having right of way, and means responsive to each of a plurality of traffic units in said one lane during right of way accord therein to reset all three of said timing means substantially simultaneously to retime their intervals concurrently.

5. In a traffic control apparatus for according right of way successively to each of a plurality of interfering traffic lanes and having means responsive to each of a plurality of traffic units in one lane during right of way accord therein to prolong such right of way for a small increment of time, the combination of two concurrently acting timing means for timing independently adjustable time intervals for determining the length of said increment of right of way prolongation, the first of such two means acting to reduce its time interval progressively responsive to the number of units of traffic on another of said lanes waiting for right of way, the second such 10 means acting to reduce its time interval gradually responsive to the length of time any traffic has been waiting for right of way on said other lane, and means responsive to each of a plurality of traffic units in said one lane during right of way accord therein to reset both of said timing means substantially simultaneously to retime their intervals concurrently.

6. In a traffic control apparatus for according right of way successively to each of a plurality 40 of interfering traffic lanes and having means responsive to each of a plurality of traffic units in one lane during right of way accord therein to prolong such right of way for a small increment of time, the combination of two concurrently 45 acting timing means for timing independently adjustable time intervals for determining the length of said increment of right of way prolongation, the first of such two means acting to reduce its time interval progressively responsive 50 to the number of units of traffic on another of said lanes waiting for right of way, and the second such means acting to reduce its time interval responsive to close spacing of moving traffic units in said one lane having right of way, and means responsive to each of a plurality of traffic units in said one lane during right of way accord 55 therein to reset both of said timing means substantially simultaneously to retime their intervals concurrently.

7. In a traffic control apparatus for according right of way successively to each of a plurality of interfering traffic lanes and having means responsive to each of a plurality of traffic units in one lane during right of way accord therein to prolong such right of way for a small increment of time, the combination of two concurrently acting timing means for timing independently adjustable time intervals for determining the length of said increment of right of way prolongation, the first of such two means acting to reduce its time interval responsive to close spacing of moving traffic units in said one lane having right of way, and the second such means 60 acting to reduce its time interval gradually re-

sponsive to the length of time traffic has been waiting for right of way on said other lane, means responsive to each of a plurality of traffic units in said one lane during right of way accord therein to reset both of said timing means substantially simultaneously to retime their intervals concurrently.

8. In a traffic control apparatus for interfering traffic lanes having right of way signals for the 10 respective lanes, traffic actuated devices for the respective lanes, and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so 15 reset said timer responsive to traffic actuation, means operated by said timer at completion of its time interval in absence of such resetting actuation to operate said control mechanism to terminate operation of the right of way signal in said one lane and timing means for reducing progressively the time interval of said timer during 20 operation of the right of way signal on said lane.

9. In a traffic control apparatus for interfering traffic lanes having right of way signals for the 30 respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so 35 reset said timer responsive to traffic actuation, means operated by said timer at completion of its time interval in absence of such resetting actuation to operate said control mechanism to terminate operation of the right of way signal in said one lane and timing means for reducing progressively the time interval of said timer during 40 operation of the right of way signal on said lane.

10. In a traffic control apparatus for interfering traffic lanes having right of way signals for the 45 respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval 50 and val, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate 55 operation of the right of way signal in said one lane and means operating responsive to actuation of the traffic actuated device on said one lane during operation of the right of way signal therein to reduce progressively the time interval of said timer.

11. In a traffic control apparatus for interfering 60 traffic lanes having right of way signals for

the respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate operation of the right of way signal in said one lane and means operating responsive to actuation of the traffic actuated device on said one lane during operation of the right of way signal therein to reduce progressively the time interval of said timer, and means operated by the last named device when non-actuated to increase said time interval slowly tending to cancel such reduction.

12. In a traffic control apparatus for interfering traffic lanes having right of way signals for the respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate operation of the right of way signal in said one lane and means operating responsive to closely spaced actuations of the traffic actuated device in said one lane during operation of the right of way signal therein to reduce the time interval of said timer.

13. In a traffic control apparatus for interfering traffic lanes having right of way signals for the respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate operation of the right of way signal in said one lane and means operating responsive to each of a plurality of actuations of the traffic actuated device in said one lane during operation of the right of way signal therein to reduce the time interval of said timer by a small increment and means responsive to the last named device when non-actuated to increase said time interval gradually tending to cancel such reduction.

14. In a traffic control apparatus for interfering traffic lanes having right of way signals for the respective lanes, traffic actuated devices for the respective lanes and a control mechanism for operating said signals responsive to actuation of

said devices, said control mechanism including a timer operated during operation of the right of way signal for one lane to provide a time interval and adapted to be reset to repeat its time interval, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate operation of the right of way signal in said one lane and means responsive to an actuation of the traffic actuated device of said other lane to reduce gradually the said time interval over a period of time during operation of the right of way signal on said one lane.

15. In a traffic control apparatus for interfering traffic lanes having right of way signals for the respective lanes, traffic actuated devices for the respective lanes and a control mechanism for operating said signals responsive to actuation of said devices, said control mechanism including a timer operated during operation of the right of way signal for one lane to provide a time interval and adapted to be reset to repeat its time interval, means connecting said timer to the traffic actuated device for said one lane having the right of way signal operated therein to so reset said timer responsive to traffic actuation, means operated by said timer at completion of its time interval in absence of such resetting actuation to operate said control mechanism to terminate operation of the right of way signal in said one lane and relay means connected to be operated to one condition from another responsive to actuation of the traffic actuated device of said another lane, and including holding means arranged to maintain said relay means in said one operated condition after any such actuation occurring when the right of way signal for said another lane is not operated and until operation of the last named right of way signal is assured, and time controlled means operated by said relay means in said one operated condition to reduce gradually said time interval of said timer during operation of the right of way signal in said one lane.

16. In a traffic control apparatus for two interfering traffic lanes, having right of way signalling mechanism having an operating cycle including one condition for according right of way to one lane and a second condition for according right of way to the second lane, traffic detectors for the respective lanes adapted to be actuated by individual units of traffic therein, a timing device initiated into operation by said mechanism in said one condition to time a short period at the end of which it actuates said mechanism to transfer the latter to its second condition, means connecting said timing device with the traffic detector of said one lane in said one condition to reset said device to repeat its timing period responsive to each traffic unit actuation and prevent for a further short period such actuation of said mechanism, further means connecting said timing device with said traffic detector of said one lane to adjust said device for a progressively shorter period in response to each of a plurality of said traffic unit actuations in said one condition and relatively long period timing means connected to be active in said one condition to adjust said timing device gradually to increase said timing period between actuations of said detector in said one lane.

17. In a traffic control apparatus for two interfering traffic lanes, having right of way signalling mechanism having an operating cycle including one condition for according right of way to one lane and a second condition for according right of way to the second lane, traffic detectors for the respective lanes adapted to be actuated by individual units of traffic therein, a timing device initiated into operation by said mechanism in said one condition to time a short period at the end of which it actuates said mechanism to transfer the latter to its second condition, means connecting said timing device with the traffic detector of said one lane in said one condition to reset said device to repeat its timing period responsive to each traffic unit actuation and prevent for a further short period such actuation of said mechanism, further means connecting said timing device with said traffic detector of said one lane to adjust said device for a progressively shorter timing period responsive to closely spaced traffic unit actuations.

18. In a traffic control system for interfering traffic lanes having a right of way signal and a mechanism adapted to operate said signal to accord right of way successively to the lanes, timing means forming a part of said mechanism and operating to time a period when right of way is accorded to said one lane and to cause termination of such accord of right of way by said mechanism at the end of said time period, means responsive to passage of a plurality of successive vehicles within time spacing of each other less than said time period in said one lane to repeatedly reset said timing means to cause successive prolongation of right of way by such time period in said one lane, a maximum timing means forming a part of said mechanism and operating to provide a maximum limit to such prolongation of right of way, and means responsive to traffic in a second lane to reduce said time period in accordance with both the number of vehicles waiting and the length of time any of such vehicles are waiting for right of way in said second lane, whereby termination of right of way in said one lane prior to such maximum limit will occur at a smaller time spacing of vehicles in said one lane.

19. In a traffic control system for interfering traffic lanes having a right of way signal and a mechanism adapted to operate said signal to accord right of way successively to the lanes, timing means forming a part of said mechanism and operating to time a period when right of way is accorded to said one lane and to cause termination of such accord of right of way by said mechanism at the end of said time period, means responsive to passage of a plurality of successive vehicles within time spacing of each other less than said time period in said one lane to repeatedly reset said timing means to cause successive prolongation of right of way by such time period in said one lane, a maximum timing means forming a part of said mechanism and operating to provide a maximum limit to such prolongation of right of way, and further means responsive to such vehicles in said one lane to reduce said time period to an extent approaching the extent that the time spacing of such vehicles is less than said time period, whereby termination of right of way in said one lane prior to said maximum limit will occur in event the actual time spacing of vehicles increases appreciably after a period of close spacing.

20. In a traffic control system for use at the intersection of two lanes including stop and go signals adapted to be displayed to the traffic thereon, vehicle actuated means in both lanes, 5 means for timing the display period of a go signal to one lane while a stop signal is displayed to the other lane and including a gas discharge tube having an anode and a cathode with a biased grid for controlling the voltage at which conduction takes place between the cathode and anode, a condenser connected to regulate the potential difference between the said anode and cathode and means for varying the voltage of said condenser from an initial to a final value 10 at which said potential difference reaches such conduction voltage, means employing such conduction between said anode and cathode to cause the said go signal to cease to be displayed in said one lane when the said condenser reaches said final voltage, means responsive to the traffic actuable means in the said one lane to vary the voltage on the said condenser toward its initial value and so cause the said go signal to continue to be displayed in said one lane for a time period and means responsive to the traffic actuable means in the other lane to reduce said grid bias progressively at a predetermined time rate after actuation on said other lane to reduce the time period during which said go signal continues to be displayed in said one lane.

21. In a traffic control system for use at the 35 intersection of two lanes including stop and go signals adapted to be displayed to the traffic thereon, vehicle actuated means in both lanes, means for timing the display period of a go signal to one lane while a stop signal is displayed to 40 the other lane and including a gas discharge tube having an anode and a cathode with a biased grid for controlling the voltage at which conduction takes place between the cathode and anode, a condenser connected to regulate the potential difference between the said anode and cathode and means for varying the voltage of 45 said condenser from an initial to a final value at which said potential difference reaches such conduction voltage, means employing such conduction between said anode and cathode to cause the said go signal to cease to be displayed in said one lane when the said condenser reaches said final voltage, means responsive to the traffic actuable means in the said one lane to vary the voltage on the said condenser toward its initial value 50 and so cause the said go signal to continue to be displayed in said one lane for a time period, means responsive to actuation of the traffic actuable means in the other lane to reduce said grid bias progressively in accordance with the number of vehicles waiting in said other lane during display of the go signal in said one lane, a second gas discharge tube similar to the first mentioned tube and having its anode and cathode connected in parallel with the anode and cathode of said first tube to have its conduction controlled similarly and to control similarly the conduction employing means, and means responsive to actuation of the traffic actuable means 55 in the other lane to reduce said grid bias of said second tube progressively at a predetermined time rate after the first such actuation on said other lane to reduce the time period during which 60 said go signal continues to be displayed in said one lane.

22. In a traffic control system for use at the 65 intersection of two lanes including stop and go signals adapted to be displayed to the traffic thereon, vehicle actuated means in both lanes, means for timing the display period of a go signal to one lane while a stop signal is displayed to the other lane and including a gas discharge tube having an anode and a cathode with a biased grid for controlling the voltage at which conduction takes place between the cathode and anode, a condenser connected to regulate the potential difference between the said anode and cathode and means for varying the voltage of 70 said condenser from an initial to a final value at which said potential difference reaches such conduction voltage, means employing such conduction between said anode and cathode to cause the said go signal to cease to be displayed in said one lane when the said condenser reaches said final voltage, means responsive to the traffic actuable means in the said one lane to vary the voltage on the said condenser toward its initial value and so cause the said go signal to continue to be displayed in said one lane for a time period, means responsive to actuation of the traffic actuable means in the other lane to reduce said grid bias progressively at a predetermined time rate after the first such actuation on said other lane to reduce the time period during which 75 said go signal continues to be displayed in said one lane.

one lane responsive to traffic actuation therein as long as display of said go signal continues in said one lane.

22. In a traffic control system for use at the intersection of two lanes including stop and go signals adapted to be displayed to the traffic thereon, vehicle actuated means in both lanes, means for timing the display period of a go signal to one lane while a stop signal is displayed to the other lane and including a gas discharge tube having an anode and a cathode with a biased grid for controlling the voltage at which conduction takes place between the cathode and anode, a condenser connected to regulate the potential difference between the said anode and cathode and means for varying the voltage of said condenser from an initial value to a final value at which said potential difference reaches such conduction voltage, means employing such conduction between said anode and cathode to cause the said go signal to cease to be displayed in said one lane when the said condenser reaches said final voltage, means responsive to actuation of the traffic actuatable means in the said one lane to vary the voltage on the said condenser toward its initial value and so cause the said go signal to continue to be displayed in said one lane for a time period, means responsive to actuation of the traffic actuatable means in the other lane to reduce said grid bias progressively in accordance with the number of vehicles waiting in said other lane during display of the go signal in said one lane, a second gas discharge tube similar to the first mentioned tube and having its anode and cathode connected in parallel with the anode and cathode of said first tube to have its conduction controlled similarly and to control similarly the conduction employing means, and means responsive to actuation of the traffic actuatable means in said one lane during display of the go signal therein to reduce the grid bias on said second tube progressively by a small amount for each of a plurality of traffic actuations, and other means connected with the grid of said second tube to be effective between such traffic actuations on said one lane for gradually increasing said grid bias.

23. In a traffic control system for use at the intersection of two lanes including stop and go signals adapted to be displayed to the traffic thereon, vehicle actuated means in both lanes, means for timing the display period of a go signal to one lane while a stop signal is displayed to the other lane and including a gas discharge tube having an anode and a cathode with a biased grid for controlling the voltage at which conduction takes place between the cathode and anode, a condenser connected to regulate the potential difference between the said anode and cathode and means for varying the voltage of said condenser from an initial to a final value at which said potential difference reaches such conduction voltage, means employing such conduction between said anode and cathode to cause the said go signal to cease to be displayed in said one lane when the said condenser reaches said final voltage, means responsive to the traffic actuatable means in the said one lane to vary the voltage on the said condenser toward its initial value and so cause the said go signal to continue to be displayed in said one lane for a time period, means responsive to actuation of the traffic actuatable means in the other lane to reduce said grid bias progressively in accordance with the number of

5 vehicles waiting in said other lane during display of the go signal in said one lane, a second gas discharge tube similar to the first mentioned tube and having its anode and cathode connected in parallel with the anode and cathode of said first tube to have its conduction controlled similarly and to control similarly the conduction employing means, and means responsive to actuation of the traffic actuatable means in the other lane to reduce said grid bias on said second tube progressively at a predetermined time rate after the first such actuation on said other lane to reduce the time period during which said go signal continues to be displayed in said one lane responsive to traffic actuation therein as long as display of said go signal continues in said one lane, a third gas discharge tube similar to the others and having its anode and cathode similarly connected, and means responsive to actuation of the 10 traffic actuatable means in said one lane to reduce the grid bias on said third tube progressively by a small amount for each of a plurality of traffic actuations, and other means connected with the grid of said third tube to be effective between such traffic actuations on said one lane for gradually increasing said grid bias.

24. In a traffic control system for two interfering traffic lanes having signals indicating when traffic is to go and stop respectively in the 15 respective lanes and means actuated by traffic in the respective lanes and a time controlled mechanism for operating said signals to display the go signal alternately to the respective lanes for time periods variable in accordance with actuation of said means by traffic on the respective lanes, a signal switching device forming a part of said mechanism having a plurality of positions through which it is adapted to be operated cyclically to so operate said signals and including at least one position for displaying a go signal to one lane and a stop signal to the other lane and at least one other position for displaying a go signal to said other lane and a stop signal to the first lane, a timing device forming a part of said mechanism for determining the time said mechanism is in said one position before it is operated to said other position, said timing device comprising a condenser, means for varying the charge on said condenser progressively from an initial value to a different final value, means responsive to such final value of charge on said condenser to operate said switching device to shift the latter from said one position to said other position, means associated with said switching device for connecting the traffic actuated means for said one lane to said condenser in said one position to vary the charge toward said initial value from any value between said initial and final values in response to actuation by traffic in said one lane, and further means associated with the switching device for connecting the traffic actuated means for the other lane to said charge responsive means in said one position of said switching device to vary the value of charge to which it is responsive from such final value toward such initial value at a predetermined slow time rate in response to actuation by traffic in said other lane, and continuing after the latter actuation while said switching device is in said one position.

25. In a traffic control system for two interfering traffic lanes having signals indicating when traffic is to go and stop respectively in the respective lanes and means actuated by traffic in the respective lanes and a time controlled

mechanism for operating said signals to display the go signal alternately to the respective lanes for time periods variable in accordance with actuation of said means by traffic on the respective lanes, a signal switching device forming a part of said mechanism having a plurality of positions through which it is adapted to be operated cyclically to so operate said signals and including at least one position for displaying a go signal to one lane and a stop signal to the other lane and at least one other position for displaying a go signal to said other lane and a stop signal to the first lane, a timing device forming a part of said mechanism for determining the time said mechanism is in said one position before it is operated to said other position, said timing device comprising a condenser, means for varying the charge on said condenser progressively from an initial value to a different final value, means responsive to such final value of charge on said condenser to operate said switching device to shift the latter from said one position to said other position, means associated with said switching device for connecting the traffic actuated means for said one lane to said condenser in said one position to vary the charge toward said initial value from any value between said initial and final values in response to actuation by traffic in said one lane, and further means associated with the switching device for connecting the traffic actuated means for said one lane to said charge responsive means in said one position of said switching device to vary the value of charge to which it is responsive from such final value toward such initial value by a small amount for each of a plurality of actuations by traffic in said one lane, and other means connected with said charge responsive means in

said one position to vary the charge to which it is responsive gradually toward said final value between such actuations by traffic in said one lane.

26. In a traffic control system for use at the 5 intersection of two lanes including stop and go signals adapted to be displayed to the traffic thereon, vehicle actuated means in both lanes, means for timing the display period of a go signal to one lane while a stop signal is displayed 10 to the other lane and including a gas discharge tube having an anode and a cathode with a biased grid for controlling the voltage at which conduction takes place between the cathode and anode, a condenser connected to regulate the potential difference between the said anode and cathode and means for varying the voltage of said condenser from an initial value to a final value at which said potential difference reaches such conduction voltage, means employing such conduction between said anode and cathode to cause the said go signal to cease to be displayed 15 in said one lane when the said condenser reaches said final voltage, means responsive to actuation of the traffic actuatable means in the said one lane to vary the voltage on the said condenser 20 toward its initial value and so cause the said go signal to continue to be displayed in said one lane for a time period, means responsive to actuation of the traffic actuatable means in said one lane during display of the go signal therein 25 to reduce the grid bias on said tube progressively by a small amount for each of a plurality of traffic actuations, and other means connected with the grid of said tube to be effective between such 30 traffic actuations on said one lane for gradually increasing said grid bias.

JOHN L. BARKER.
